UNITED STATES PATENT OFFICE.

CHARLES P. HOWE, OF AUSTIN, TEXAS.

GATE.

SPECIFICATION forming part of Letters Patent No. 323,684, dated August 4, 1885.

Application filed March 24, 1885. (No model.)

To all whom it may concern:

Be it known that I, CHARLES P. HOWE, a citizen of the United States, residing at Austin, in the county of Travis and State of Texas, 5 have invented certain new and useful Improvements in Gates, of which the following is a specification, reference being had therein to the accompanying drawing.

My invention relates to improvements in 10 gates of that class known as "tilting and folding" gates, and is designed to produce a gate that will automatically lock itself when down and close the passage by means which will not interfere in the least with the operation of 15 tilting.

The improvement consists, essentially, in the locking and operating mechanism.

In describing the device reference is had to the annexed drawing, showing a perspective 20 view of the gate, the dotted lines indicating the position assumed when the gate is tilted and folded.

The gate proper is formed of slats or rails A, pivoted to battens B, and the whole pivoted at one end to a post, C, set in the ground. 25 Wires D may also be used stretching from batten to batten, and having pivotal connections therewith.

The top rail is extended beyond the 30 supporting-post, and there carries a weight, E, counterbalancing the weight of the gate.

A diagonal rail extends wholly or partly 35 across the gate, and is composed of two parts, F and G, one constructed preferably shorter than the other. A joint similar to those used in rules connects the two pieces, and is so formed that no force, except one from below, will move the two parts out of line when once in that position.

40 Pivoted to the pintle of the joint, one on each side, are rods H, connected to the shorter

arms of lever-arms I, fulcrumed to a cross-bar, K, on the top of the post C.

By raising the jointed portion by means of the levers the distance between the pivotal 45 points of the diagonal rail F G is shortened, and at the same time the posts B not pivoted to the battens C are made to approach and rise.

When the rods H have passed the perpendicular, the weight E will carry the extension of the top rail toward the post C and cause the gate to assume the position shown in dotted lines in the drawing.

A reverse of the above operation will close 50 or more properly lower the gate, and the abutting portions of the diagonal rail will effectually lock the gate.

I am aware that tilting counterbalanced gates are old, and I am also aware that locking-jointed diagonal rails are old in sliding gates, and that tilting gates have been operated by levers heretofore; but I am not aware that counterbalanced tilting gates have been provided with diagonal-jointed locking-rails 60 65 and operated by levers, the connection from the levers passing to and joining the rail at the said joint.

I claim—

The combination, with a tilting counterbalanced gate, of a diagonal rail formed of two parts normally in a line one with the other and joined by a rule or locking joint, and operating-levers having connection with the rail at the joint, substantially as and for the purpose specified. 70 75

In testimony whereof I affix my signature in presence of two witnesses.

CHARLES P. HOWE.
